UNITED STATES PATENT OFFICE.

ARTHUR A. JOHNSON, OF NEW YORK, N. Y., ASSIGNOR TO UNDERWOOD TYPEWRITER COMPANY, OF NEW YORK, N. Y., A CORPORATION OF DELAWARE.

TYPE-WRITING MACHINE.

1,278,156.

Specification of Letters Patent. Patented Sept. 10, 1918.

Application filed June 7, 1917. Serial No. 173,282.

To all whom it may concern:

Be it known that I, ARTHUR A. JOHNSON, a citizen of the United States, residing in borough of the Bronx, in the county of the Bronx, city and State of New York, have invented certain new and useful Improvements in Type-Writing Machines, of which the following is a specification.

This invention relates to an improvement 10 in typewriting machines, and more particularly to means for enabling various work-sheets to be collated upon one another to receive type-impressions from the machine.

In the present invention, a table located 15 above the platen at the delivery side thereof, is provided with means to enable the collating of work-sheets placed in the machine. This collating table extends a considerable distance up from the platen so that large 20 sheets may be used.

To introduce the work-sheets into a type-writing machine, the operator usually places the leading edge of the sheet on the paper table at the rear of the machine, and then 25 moves the sheets around beneath the platen. The sheets are placed face downward, so that when moved around to printing position the face will be up to receive type-impressions.

To facilitate the insertion of the work- 30 sheets, the present invention provides means whereby the sheets may be inserted from the front of the machine. This arrangement relieves the operator of the necessity of reaching over or around the collating board, to 35 introduce the sheets to the machine. The operator instead introduces the sheets from the front of the machine. With this arrangement the sheets are at all times face upward, and therefore may be more easily collated.

40 This arrangement also enables the operator to readily collate the sheets individually; that is, one of the sheets may be placed in the machine and positioned upon the collating table, so that the first line to be written 45 upon is at the writing line, and the next sheet with a carbon may be placed in the machine and collated, so that its first line to be written upon is at the writing line, and so on until the sheets are assembled. The ar- 50 rangement is such, that the work-sheets may be engaged by the feed rolls while still in the original collated position on the collating table.

It is sometimes desired that checks or 55 other small work-pieces be collated with

larger work-pieces. These small work-pieces are usually so small as not to extend up to the collating table. For the purpose of collating these small work-pieces and for other purposes, the present invention provides collating devices directly upon the platen. These collating devices on the platen may be used to the exclusion of the collating devices on the table, under some circumstances, and the collating devices on the table may also 60 be used to the exclusion of the collating devices on the platen. Both collating devices may also be used simultaneously when it is desired to collate both small and large work-sheets.

In the present invention, the collating table located above the platen or on its delivery side is provided with collating devices in the form of a series of studs arranged in rows, one row at each side of the collating 70 table, in position to be engaged by perforations in the work-sheets. These studs are arranged so that they are normally in an ineffective position below the surface of the paper table, to permit free movement of the 75 work-sheets during the course of writing. The studs are arranged to be manually or automatically protruded through the collating table when it is desired to collate the 80 sheets thereon.

To facilitate the insertion of the sheets at the front of the machine, the platen may be arranged to be movable upward and away from the type guide, the ribbon vibrator and other parts, usually found in visible type-writing machines, that obstruct the free passage at the front of the machine of the bottom edge of the sheet. To guide the work-sheets past these and other obstructions to the usual paper apron beneath the platen, an 85 auxiliary paper guide may be provided. This paper guide may be arranged to normally occupy a position of disuse or retirement beneath the platen, and the arrangement may be such that when the platen is 90 moved to paper-receiving position, the auxiliary guide or directrix is moved up to position to properly guide the bottom edge of the sheet into the machine. This auxiliary guide may be provided with a scale or means along 95 its top edge for indicating the portion of the platen which will be the writing line when the platen is returned to normal writing position. To permit this movement of the 100 platen, the platen may be mounted in a frame, 105

which, in turn, is pivotally mounted in a platen-shift frame of the ordinary typewriter carriage, and this arrangement will not in any way alter the action of the usual case-shift mechanism.

The collating studs are projected automatically to an effective position after the usual feed rolls have been released when the platen moves to receiving position. This 10 may be done by providing a connection between the movable platen and the collating studs, which act through the medium of the feed-roll release mechanism, so that the feed-roll release and the movable platen jointly 15 control the collating pins. This is done so that the collating pins will only be projected by the movements of the platen when the feed rolls are released, and so that when the feed rolls are again caused to engage the 20 platen, while the platen is still in receiving position, the collating studs will be retracted.

The collating studs on the platen may be arranged in rows, each row being in line with 25 a row of studs in the collating table. There may be one pair of collating pins for each line of writing on the platen. A finger-piece may be provided so that when operated, only the row at the writing line will be protruded 30 for collating purposes. The tops of these studs may be normally flush with the platen.

The connections between the platen and the line-space mechanism may be maintained during the movements of the platen for receiving the sheets by means of a pair of gears meshing with an intermediate pinion.

Other objects and advantages will herein-after appear.

In the accompanying drawings, 40 Figure 1 is a front view in elevation, showing the parts in their normal typewriting position.

Fig. 2 is a vertical section taken from front to rear, showing the parts in their normal typewriting position, as in Fig. 1.

Fig. 3 is a view similar to Fig. 2, except that the platen has been raised, the feed-rolls released and the collating studs projected preparatory to the collating of the 50 sheets and the insertion of the same at the front of the platen.

Fig. 4 is an end view in elevation on a somewhat smaller scale than Figs. 2 and 3, showing how the movement of the platen 55 when collating does not interfere with its shifting between upper and lower-case writing.

Fig. 5 is a fragmentary top plan view of the front portion of the platen, with parts broken away to show how the platen-collating studs are operated. In this view, the collating studs are shown receded to an inoperative position.

Fig. 6 is a top plan view, showing the 60 platen and its connections also broken away

to show the collating-stud operating mechanism, as in Fig. 5, except that the pair of studs, corresponding to the location of the piece of work at the line of writing, has been projected to effective positions.

Fig. 7 is a detail view partly in end elevation, and partly in section, showing the manner of supporting the collating studs in the platen, and also showing one pair of studs as projected to a collating position.

Fig. 8 is a detail section taken on the line 8-8 of Fig. 6, and illustrating the worksheet guide, and also the means for operating the platen-collating studs.

Fig. 9 is a detail view of the pressure 80 feed-rolls, showing the means of locking them in their position away from the platen, so as to prevent their accidental reengagement with the platen. The locking means also prevents the accidental retirement of 85 the collating studs to an ineffective position.

The platen 1 is mounted on an axle 2, which is supported to rotate in an auxiliary frame 3. The auxiliary frame 3 is mounted to swing about axially aligned stub shafts 4, 90 which, in turn, are mounted on the usual platen frame 5. The platen frame 5 is supported by the carriage 6, which travels in the usual way on the rail 7 at the rear, and on the usual rail at the front of the machine. For the purpose of shifting the platen frame 5 and with it the auxiliary platen frame 3 and the platen 1, there is provided the usual case-shift frame 8, 95 whereby both upper and lower-case characters may be written by the type-bars indicated in dotted lines at 9, Fig. 2. The platen frame 5 is supported in the way common to an Underwood typewriting machine, which includes rollers 10 riding on the rail 100 11 of the case-shift frame 8, and swinging arms 12 pivoted on the carriage at 13 and engaging studs 14 provided on the platen frame 5.

In order to rotate the platen by the usual 110 line-space mechanism, there is provided a supplementary axle 15 mounted in the platen frame 5, normally in line with the platen axle 2, but not integral therewith. This supplementary axle 15 may be turned 115 by a knob 16 thereon for a number of line-spaces back or forth, and may also be operated by the usual line-space mechanism for line-space movements of the platen predetermined extents. This line-space mechanism includes a line-space lever 17, Fig. 6, and is of a type common in Underwood typewriting machines. The line-space lever 17 is connected to operate a slide 18, which carries a pawl 19 to drive a ratchet wheel 120 20. The ratchet wheel 20 is secured to the supplementary axle 15.

In order that the platen 1 may be driven from the supplementary axle 15, which receives said movements for line-spacing the 125 180

platen, from the knob 16 and lever 17, there is provided a train of gearing which connects the supplementary axle 15 with the platen axle 2. This train of gearing includes a gear 21, secured to the supplementary axle 15, driving a broad pinion 22 meshing with and driving a gear 23 corresponding to the gear 21, but secured to the platen axle shaft 2. The pinion 23 is mounted for bodily rotation co-axially with the shaft 4, so as to permit the swinging of the platen with the gear 23 about the axis of the shaft 4 without interfering with the driving connection from the platen to the knob 16 and the line-space mechanism. Thus the proper relation between the platen and line-space mechanism is constantly maintained.

The right-hand end of the platen axle 2 may project, as seen in Fig. 1, and be provided with a knob 24 similar to the knob 16. Provision is made for permitting a relative motion between this portion of the platen axle 2 and the platen frame 5, by cutting away the latter, as indicated in Fig. 4 at 25, to form a slot of sufficient length to allow for the relative up-and-down movement of the platen 1 with respect to the platen frame 5.

36 The platen frame 5 is provided with the usual paper-apron 26, whereby the work-sheet may be inserted on the platen from the rear for any ordinary typewriting if desired. The platen shield 27 takes the paper, 35 when inserted from the rear, from the paper-apron 26 and guides it around the platen. When the platen is rotated, feeding the paper around with the platen is accomplished by means of the usual pressure feed-rolls 28 and 29 mounted on swinging frames 30 and 31, which are mounted on a rod 31 secured to the auxiliary frame 3. Normally, springs 32, Figs. 1 and 9, urge the pressure feed-rolls 28 and 29 into close 40 contact with the platen 1 or work-sheets carried thereby.

To spread the rolls 28 and 29 apart from the platen, and thus enable the work-sheet to be readily placed upon the platen, a feed-roll release finger-piece 33 is provided. This finger-piece, when depressed, rocks about a pivot 34 to draw up on a link 35, so as to rock the arm 36 secured to a rock shaft 37. The rock shaft 37 is provided with flat sides 38 and 39 at intervals, which, when the rolls are in gripping relation with the platen, are adjacent the inner sides of arms 40 and 41 secured, respectively, to the frames 30 and 31. When the release finger-piece 33 is depressed, however, the rock shaft 37 turns in its bearings, to bring the other sides 42 and 43 thereof into engagement with the inner sides of the arms 40 and 41, thereby spreading the arms 40 and 41 apart, inasmuch as these sides 42 and 43 are located at greater

distances from each other than the sides 38 and 39. The spreading of the arms likewise spreads the frames 30 and 31, so as to withdraw the pressure rolls 28 and 29 from co-operative relation with the platen 1.

It will be noted in passing because of the flat sides 42 and 43, that the pressure feed-rolls 28 and 29 are locked in their disengaged position, and can only be restored by a positive return of the release finger-piece 33. The paper shield 27 is supported on the auxiliary frame 3, so that it will move with the pressure feed-rolls 28 and 29 and the platen 1 when said auxiliary frame 3 is moved.

Normally, the auxiliary frame 3, together with the platen 1, is held in a depressed position, corresponding to that of Figs. 1, 2 and 4, by means of a latch 44 carried thereby, which engages a pin 45 carried by the platen frame 5. Springs 46 act to swing the auxiliary frame 3 about its pivot 4 when the latch 44 is released by a depression of a finger-piece 47, carried thereby. The latch and its finger-piece 47 are integral, so as to move as a unit. To operate the release key or finger-piece 33, by the operation of the finger-piece 47, a pin 48 thereon overlies and engages the lever of the release key 33. The member 47, on which the latch 44 is formed, is formed so as to permit an extra movement thereof relative to the pin 45, for the purpose of operating the release key 33. That is to say, there is provided a cut-out portion 49, Fig. 3, which is bordered on the opposite side from the latch 44 with an extension 50 limiting the movement of the finger-piece 47. A spring 51 automatically returns the finger-piece 47 and the latch 44, as they are integral, when the pressure thereon is released. This return, however, only brings the parts to the position of Fig. 3, as, in order to reengage the latch 44 with the pin 45, it is necessary to depress the platen 1 and its auxiliary frame 3 against the tension 100 of the spring 46, as for instance, by means of a handhold 52, Fig. 6.

It will thus be seen that with the raising of the platen 1 to a position to permit the insertion of the work-sheets at the front thereof, the pressure feed-rolls 28 and 29 are also moved to their inactive position and locked in this position.

To assist in guiding the work-sheets on the platen 1 from the front, there is provided an auxiliary guide 53, which is in the form of a bail swingingly mounted on the platen axle 2 and forming an extension of the paper shield 27. The upper edge of the guide 53, indicated at 54, may be used to act as an auxiliary line gage, inasmuch as the platen 1, when moved to its collating position, moves away from the usual line gage indicated at 55, Fig. 2. The guide 53 also helps the lower edge of the work-sheets 125

in clearing the ribbon and its supporting mechanism indicated at 56, Fig. 2, which usually obstruct the insertion of sheets bottom first at the front of the platen. The 5 usual ribbon is indicated at 56*, threaded through a vibrator 56.

The guide 53 is normally in a depressed position when typewriting, so as to clear the line gage 55, the ribbon mechanism 56 and 10 the type-bars 9. When collating, however, the guide 53, being mounted on the platen axle 2, moves up with the platen at the same speed as the latter for a portion of the platen's movement. In order to move this 15 guide 53 an added amount so as to bring its upper edge nearer the top of the platen, it has an accelerated movement during the latter portion of the upward movement of the platen. For this purpose, there is provided 20 an arm 57 on the bail of the guide 53, which extends rearwardly from the platen axle 2 to such a position as to engage a fixed pin 58 secured to the platen frame 5, and relatively to which the auxiliary frame 3 swings. 25 That is to say, the auxiliary frame 3 is provided with a slot 59 into which the pin 58 projects, permitting the auxiliary frame 3 to swing upwardly. The arm 57 of the guide 53 overlaps the lower portion of the slot 59, 30 as indicated in Fig. 2, so that during the latter portion of the upward movement of the frame 3 and the platen 1, the arm engages the pin 58 and is swung relatively to the frame 3 against the tension of a spring 60, 35 which normally holds the guide 53 in its lowermost position. Thus, the pin 58 causes the guide 53 to swing about the platen axle 2, so as to raise the upper edge of the guide 54 higher than it would if it depended 40 only on this movement with the platen and the auxiliary frame 3. This enables the easy insertion of the work-sheets on the platen from the front, by guiding the lower edges of the work-sheets around the platen to the 45 bite of the feed-rolls.

When collating work-sheets, such as bills, of fair size, a collating board 61 is used, which extends upwardly from the front side of the platen to a position considerably above the same. This collating board 61 is provided with studs 62 on each side thereof, to engage perforations provided in the side margins of the work-sheets. Normally, these studs 62 are receded below 55 the face of the collating board 61, as in Fig. 2, so that they will not obstruct the movement of the work-sheets as they come from the platen in a normal typewriting operation. When the platen 1 is raised to a 60 collating position, however, the studs 62 are also projected to an effective collating position.

The studs 62 are mounted on blocks 63, which are guided for movement by the studs 62 themselves extending through perfora-

tions 64 in the collating board 61. These blocks 63 are manipulated by a slide 65, which has inclined cam slots 66 engaging pins 67 provided on the blocks 63. Normally, a spring 68 holds the slide 65 in such 70 position that the pins 67 will be in the upper portions of the cam slots 66, as in Fig. 2, so that the blocks will be held in their rearmost position and the studs 62 likewise held in a receded ineffective position. 75

The slide 65 is moved against the tension of the spring 68 through the medium of the feed-roll release key 33, which, it will be remembered, is operated when the platen is shifted to its upper collating position. For 80 this purpose, the rear arm 69 of the release key 33 is provided with a pin which extends into a slot 70, Figs. 2 and 3, in a link 71 connected to the slide 65.

The releasing movement of the key 33 85 will be idle with respect to the link 71, because of the slot 70, so that the rolls 28 and 29 will be withdrawn from the platen before the studs 62 are projected. When the key 33 now moves upwardly, with the release auxiliary frame, it will force the slide 65 90 upwardly against the tension of its spring 68 to the Fig. 3 position, when the studs 62 will be carried to their projecting position. This lost motion between the release 95 key 33 and the slide 65 enables the studs 62 to be moved out of the perforations in the work-sheets after collating of the work-sheets, when the pressure feed-rolls 28 and 29 are brought into play to grip the work-sheets to the platen, but before the platen is returned to normal position, thereby preventing the tearing of the work-sheets, due to a premature returning of the platen to 100 normal position. 105

Inasmuch as the feed-roll release key 33 projects the studs 62 against the tension of the spring 68, a utility of the locking action provided by the flat sides 42 and 43, Fig. 9, is seen. These flat sides will positively lock 110 the studs in their projected position, and the feed-rolls in their released position until the operative restores the release key 33 to its normal position.

When collating small work-sheets, such as 115 bills or checks, which will not bridge the distance from the platen to the lower studs 62 on the collating board, platen-carried studs 72 are used. There are two series of these studs, one on each end of the platen, and there is one stud in each series for every line-space of the platen. Normally, the studs 72 are receded within the platen to a position such that their outer ends are flush with the platen, thereby forming a continuous 120 surface. The pair of studs which will bring to the printing point the initial lines of writing of short bills or sheets, may be projected to permit perforations in these short bills or sheets to engage the studs for arranging 125 130.

them relative to each other or to larger work-sheets collated on the studs 62.

For this purpose, each pair of studs 72, in addition to being guided by radial openings 73 in the platen 1, is connected to a shift bar 74. Each of the studs 72 is provided with an inclined groove 75, Figs. 5 and 6, which engages a camming section 76 inclined to the general length of the bar 74, 10 and formed by cutting out notches in the opposite edges of the bar. When the bar 74 is moved endwise or lengthwise of the platen, it shifts a pair of the studs 72. The normal position of the studs and the bar is 15 shown in Fig. 5, which position is maintained by the arms of a spider spring 77.

When necessary to project a pair of the studs or pins 72, a shift lever 78, Figs. 1 and 8, is swung about its pivot, so as to bring a 20 cam 79 thereon into engagement with the projecting end 80 of the particular bar 74 corresponding to the line of writing of the platen. This shifter will thus force the bar 74 from the Fig. 5 position to the Fig. 6 25 position against the tension of the spring 77, thereby protruding the pair of the collating studs 72 which happen to correspond with the line of writing, or, at least, corresponding to perforations in the work-sheets, which 30 will bring the desired lines of writing in register with each other, and in register with the printing point of the typewriter.

It will be noted that the bars 74 are made of flexible material, so that the collating studs 72 may be inserted through their openings 73 and readily cam aside the bars 74 to engage their notches 75 with the cam sections 76. This enables the mechanism to be rapidly assembled. The pins 72 are cam-shaped at 81 for this purpose. The projection of the bars 74 at both ends through slots in the end plates of the platen prevents their getting out of position, and guides them in their movement.

45 The slide 65 is justified in its up-and-down movement, so as to project the collating board studs 62 evenly on opposite sides, by means of a pair of gears 82 secured to a shaft 83, Fig. 1, and engaging racks 84 provided on the slide 65.

The operation of the device will be readily understood when taken in connection with the above description. For collating or assembling two or more work-sheets, such 55 as bills or the like, so that differently located lines will coincide with each other, the platen 1 is raised by operating the finger-piece 47 to release the latch 44. This enables the spring 46 to lift the platen, so 60 as to space it relatively to the line gage 55 and the ribbon mechanism 56.

The finger-piece 47, through the intermediary of the pin 48, operates the release key 33 to release the pressure feed rolls 28 and 35 29. The upward movement of the platen

carries with it the auxiliary guide 53, which moreover has an accelerated movement relative to the platen due to the co-action of the pin 58 and the arm 57 on the guide 53. Thus the guide 53 and the platen are brought up 70 to a position such that they will readily receive the bottom edges of the work-sheets, whereby the work-sheets may be inserted on the platen from the front.

The extent of insertion of the work-sheets, 75 and thus the assembling to bring the desired lines on different sheets in register with each other, may be determined by placing them on the studs 62, which have been projected with the upward movement of the platen. 80 The work-sheets may be provided with perforations on either one side or the other or on both sides, so as to coöperate with one or more, preferably two, of the studs 62.

When the sheets have been assembled in 85 this way, so as to bring predetermined lines on the different sheets in register with each other, then the platen can be restored to its normal first position by pressure on the finger-piece 52. Prior to this return movement, the release key 33 is raised so as to unlock the pressure rolls 28 and 29 and bring them to an effective position. The restoration of the finger-piece 33 permits the withdrawal of the studs 62 by means of the 90 spring 68 to an ineffective position after the pressure rolls engage the platen, so that the sheets will be held by the feed-rolls on the platen just as they were when the studs 62 were in engagement with the work-sheets, 95 thereby eliminating the danger of disarrangement of the work-sheets.

If short work-sheets, such as bills or checks, are to be collated and printed upon, the length may not be such as to reach the 100 studs 62. In such a case, the platen-carried studs 72 are used. These studs, which are mounted at the ends of the platen outside of the printing field thereof, are projected in pairs, one pair at a time, by the hand-lever 110 78, so that they may engage properly-positioned perforations provided on the bills or checks being assembled. When the platen-carried studs 72 are used, the platen 1 may 115 be raised as before, with the raising of the guide 53, so that the bottom edges of the work-sheets can be readily inserted on the platen at the front.

The hand-lever 78 may be retained in any 120 of its positions by a detent spring 85 co-operating with holes or depressions 86, Figs. 6 and 8, formed in the auxiliary frame 3.

With the above arrangement, it will be seen that it is possible for the operator to 125 collate the sheets individually; that is, one of the sheets may be introduced between the platen and the feed rolls, from the front, by means of the shield 53, and then collated upon the studs 62, so that the first line to be written upon is in line with the gage 54. 130

Then the second sheet is introduced by the shield 53, and in a like manner collated upon studs 62, so that its first line to be written upon is in line with the gage 54, and so on, 5 until various sheets are collated. This method of handling the sheets is of great advantage, especially where some of the sheets are left in the machine to make a record of all the transactions which take place, such 10 as in condensed billing. It is also an advantage, in that the operator, during a collating operation, has the working faces of the sheets in full view.

When a check or other small work-piece 15 is to be collated upon the pins 72 carried by the platen, the said small work-piece will be introduced to the platen while the studs 72 are in a retracted position within the platen. After the work-pieces have been placed in 20 the machine, the collating studs in the platen are protruded by means of the finger-piece 73. The sheets are then positioned on said pins.

Variations may be resorted to within the 25 scope of the invention, and portions of the improvements may be used without others.

Having thus described my invention, I claim:

1. The combination with a platen, of a 30 collating board coöperating with said platen for the purpose of assembling two or more work-sheets located above said platen at the front, whereby work-sheets may extend around said platen and lie on said collating board at the same time, and means for shifting said platen up toward said collating board, so as to bring the front surface of said platen closer to said board for assembling the sheets on said platen and said 35 board simultaneously.
2. The combination with a platen, of elements coöperating with said platen at the front thereof to insure proper typewriting, means for shifting the platen away from 40 said elements to give a clear space such that work-sheets may be inserted on said platen backward, and a guide movable with and relatively to said platen, to form a chute between its surface and the surface of said 45 platen directing the lower edges of work-sheets past said elements and around the platen.
3. The combination with a platen, of elements coöperating with said platen at the 50 front thereof to assist in effecting proper typewriting operations, an axle for rotatably supporting said platen, means for shifting said platen and said axle bodily relatively to said elements, and a guide extending 55 across the front of the platen and pivotally mounted on said axle, so as to swing with said platen and relatively to said platen, whereby said guide may be shifted to deflect the lower edges of work-sheets past said 60 elements.

4. The combination with a platen, of means for shifting said platen bodily relatively to the printing point, a guide for assisting in deflecting work-sheets onto said platen backward by engaging the lower 70 edges of said work-sheets, said guide being below the printing point, and means for concomitantly shifting said guide above the printing point and raising said platen above the printing point, so as to render the platen 75 more accessible, and enable the work-sheets to be inserted reversely at the front of the platen more easily.

5. The combination with a platen, of a collating board located above and at the 80 front of said platen, so that work-sheets may lie on said collating board and around said platen at the same time, collating studs normally receded to an ineffective position, and means for concomitantly shifting said platen 85 bodily closer to said collating board and projecting said studs to an effective position, whereby the work-sheets may be relatively positioned to each other and said collating board and at the same time inserted around 90 said platen.

6. The combination with a platen, of two series of impaling studs circumferentially disposed about said platen at line-space intervals, said studs being normally receded 95 to an ineffective and non-obstructing position, and means for projecting said studs selectively in pairs, so as to enable the collating of work-sheets having perforations to engage the studs when projected.

7. The combination with a platen, of two series of impaling studs arranged about said platen and normally receded within the platen to ineffective positions, bars connecting said studs in pairs, and means for shifting said bars individually so as to project a pair of studs to effective positions, whereby work-sheets having perforations may be impaled on said studs to collate them.

8. The combination with a platen, of a 111 pair of impaling studs mounted on said platen and normally receded to a position with their outer ends flush with the outer surface of said platen, a bar engaging both said studs and having cam surfaces to shift 115 said studs from a receded position to a projected position, and means for shifting said bar, so as to determine the effectiveness of said studs, whereby work-sheets having perforations may be collated by impaling them 120 on said studs.

9. The combination with a platen, of a paper apron for directing work-sheets around said platen, a guide forming a continuation of said paper apron at the front 125 thereof, and means for concomitantly shifting said paper apron away from said platen to make room therebetween and raising said guide relatively to said apron, so as to form a continuation thereof, thereby aiding the 130

insertion of work-sheets on the platen from the front.

10. The combination with a platen, of a paper apron for said platen, a shiftable guide forming an extension for said apron at the front of said platen, whereby work-sheets may be introduced on said platen from the front, a spring for raising said platen, a spring for maintaining said guide in fixed relation with respect to said platen, while moving with said platen, and means for enabling said first-mentioned spring to overcome said second-mentioned spring, so as to raise said guide relatively to said apron and said platen.

11. The combination with a platen, of a collating board coöperating with said platen to assemble work-sheets on said platen, normally-receded impaling studs on said collating board, means for shifting said platen to a collating position, and connections enabling said studs to be automatically projected to a collating position when said platen is shifted to a collating position.

12. The combination with a platen, of a collating board coöperating with said platen to assemble work-sheets on said platen, impaling studs on said collating board normally located in a receded position, feed rolls normally in intermittent contact with said platen to coöperate in feeding work-sheets around said platen, and means for automatically releasing said feed rolls and projecting said studs to a collating position, whereby work-sheets may be introduced between said platen and said feed rolls, and impaled on said studs at the same time.

13. The combination with a platen, of a collating board coöperating with said platen to assemble sheets on said platen, normally-receded collating studs on said board, feed rolls coöperating with said platen to aid in the feeding of work-sheets around said platen, and means for intermittently releasing said feed rolls, projecting said studs to a collating position and raising said platen to a closer proximity to said collating studs, whereby work-sheets may be impaled on said studs and introduced at the front of the platen between said feed rolls and said platen at the same time.

14. The combination with a platen, of feed rolls coöperating with said platen, a collating board coöperating with said platen, normally-receded collating studs projectable to assist in assembling work-sheets on said platen, releasing means for said feed rolls, and connections from said releasing means to said collating studs for projecting said studs with the release of said rolls, said connections having lost motion therein, so as to permit the recession of said studs prior to the return of said feed rolls into feeding relation with the platen.

15. The combination with a platen frame

including a platen, of a spring for raising said frame to carry the platen from writing position to a collating position, a latch for holding said platen in a normal typewriting position against the tension of said spring, a finger-piece depressible to release said latch, and a finger-piece depressible to restore said platen to writing position and put it under the control of the latch.

16. The combination with a platen, of a spring for shifting said platen from a normal typewriting position to a collating position, a latch for locking said platen against the action of said spring, feed rolls coöperating with said platen to feed work-sheets around said platen, and means for releasing said latch, acting subsequently to release said feed rolls, so that when said platen is moved to a collating position there will be a space between said feed rolls and said platen, permitting the easy insertion of work-sheets on said platen.

17. The combination with a platen, of a spring for shifting said platen from a normal typewriting position to a collating position, feed rolls coöperating with said platen, a release for said feed rolls, a finger-key lever having a pip thereon to operate said rolls, and a latch thereon to lock said platen in a typewriting position.

18. The combination with a platen, of a collating board coöperating with said platen, impaling studs on said collating board, feed rolls coöperating with said platen, means for manipulating said feed rolls between effective and ineffective positions, including a lug for locking said feed rolls in effective and ineffective positions, and connections enabling said lug to maintain said impaling studs in their projected positions.

19. The combination with a platen, of a collating board coöperating with said platen, impaling studs on said collating board, feed rolls coöperating with said platen, means for manipulating said feed rolls between effective and ineffective positions, including a lug for locking said feed rolls in effective and ineffective positions, connections enabling said lug to maintain said impaling studs in their projected positions, and spring means for automatically receding said studs to an ineffective non-obstructing position when said lug is released.

20. The combination with a platen, of elements coöperating with said platen for the proper positioning and feeding of work-sheets on said platen, a collating board coöperating with said platen to enable the assembling of work-sheets on said platen, normally-receded impaling studs on said collating boards, and a common means for placing said elements and said platen in a condition to receive work-sheets as assembled at the front of the platen, and automatically

projecting said studs to an impaling position, whereby work-sheets may be impaled on said studs and inserted at the front of said platen at the same time.

21. In a typewriting machine, the combination with a platen and feed rolls therefor, of a collating table extending upwardly from the front of said platen, said table being arranged so that the work-sheets may be 10 collated thereon while in position to be engaged by the feed rolls, and means for enabling the work-sheets to be introduced to the platen from the front of the machine, so that the work-sheets may be placed one 15 upon the other, face upward, on the collating table.

22. In a typewriting machine, the combination with a platen and feed rolls therefor, of a table extending upwardly from 20 the front of the platen, having means for collating work-sheets, said table being arranged so that the work-sheets may be collated thereon while in position to be engaged by the feed rolls, means for enabling the work-sheets to be introduced to 25 the platen from the front of the machine, so that work-sheets may be collated one upon the other, face upward, on the collating table, and means carried by the platen for 30 collating a work-sheet whose size and proportion do not permit it to be collated upon the collating table while still in position to be engaged by the feed rolls.

23. In a typewriting machine, the combination with a platen, of a frame wherein 35 said platen is mounted for moving said platen for the purpose of permitting the positioning of work-sheets relatively thereto, a second frame wherein said platen frame is carried, said second frame being relatively stationary when the platen frame is moved for permitting the positioning of work-sheets relatively thereto, line-spacing mechanism mounted in said second frame, 40 connections between said line-spacing mechanism and the platen, whereby movements of the line-spacing mechanism are transmitted to the platen, a finger-piece connected to said line-spacing mechanism, and 45 a finger piece at the other end of said platen rigidly connected thereto and at all times concentric with the platen.

24. In a typewriting machine, the combination with a platen, of a frame wherein 50 said platen is mounted for moving said platen for the purpose of permitting the positioning of work-sheets relatively thereto, a second frame wherein said platen frame is carried, said second frame being relatively stationary when the platen frame is moved for permitting the positioning of work-sheets relatively thereto, line-spacing mechanism mounted in said second frame, 55 connections between said line-spacing mechanism and the platen whereby movements

of the line-spacing mechanism are transmitted to the platen, a finger-piece connected to said line-spacing mechanism, and a finger-piece at the other end of said platen rigidly connected thereto and at all times 70 concentric with the platen, said second frame being slotted to permit the movements of the last-named finger-piece with the platen for paper-handling purposes.

25. The combination with a platen and 75 a ribbon vibrator in front thereof, of a paper guide beneath the platen, and a support for said guide adapted to permit it to be swung up in front of the platen to guide a sheet downwardly past said vibrator. 80

26. The combination with a platen and a ribbon vibrator in front thereof, of a paper guide beneath the platen, a support for 85 said guide adapted to permit it to be swung up in front of the platen to guide a sheet downwardly past said vibrator, and a collating table above the platen on which sheets are adapted to be collated to be slid upon the guide.

27. The combination with a platen frame 90 and a platen journaled therein, of a plurality of pins adjacent one end of the platen mounted to be projected from its surface to adjust a sheet thereby, and a finger-piece upon said frame adapted to selectively project said pins. 95

28. The combination with a platen, of a collating table on which sheets may be adjusted previous to passing them around the platen, collating pins in said table, and 100 collating pins normally within said platen but mounted to be projected therefrom to enable work-sheets to be co-operatively adjusted on the table pins and the platen pins.

29. The combination with a platen, of a 105 collating table on which sheets may be adjusted previous to passing them around the platen, collating pins normally beneath the surface of the table, collating pins normally within the platen, and separate means 110 for projecting the platen pins and the table pins.

30. The combination with a revoluble platen, of collating pins normally beneath the surface thereof, and arranged in groups 115 in each of which the pins are co-operative, and means for selectively projecting such groups of said pins above the platen surface while leaving others unprojected.

31. The combination with a revoluble 120 platen, of collating pins thereon upon which the work may be impaled to position the same for being typed, said pins mounted at the ends of the platen outside of the printing field thereof, said pins normally 125 beneath the surface of the platen, a platen frame in which said platen is journaled, operating devices for projecting said pins, a finger-piece for operating said devices, and means distinct from said pins for hold- 130

- ing the work upon the platen where it is located by means of said pins.
32. The combination with a revoluble platen, of a circumferential row of collating pins normally beneath the surface thereof, and means for selectively projecting said pins above the platen surface.
33. The combination with a revoluble platen, of a circumferential row of collating pins normally beneath the surface thereof, a bar extending from each pin to the end of the platen, and a cam adjacent the end of the platen adapted to be effective on said bars to selectively project said pins.
34. The combination with a platen comprising projectable pins, of a collating table for delivering work-sheets to the platen, pins upon said table normally beneath the surface thereof, but constructed to be projected to align work-sheets thereby, and a finger-piece operable to project a pin automatically from the platen at such a point removed from the table pins that work-sheets aligned separately by the projected platen pin and a table pin will be collated properly relatively to each other.
35. The combination with a revoluble platen having studs to engage a work-sheet, and from which the work-sheet is releasable, of a collating board also having studs to engage the work-sheet, and from which the work-sheet is also releasable, the studs upon the platen having a predetermined relationship to the studs upon the collating table, whereby both small and large work-sheets may be collated.
36. The combination with a revoluble platen and coöperative devices tending to obstruct the insertion of work-sheets at the front of the platen, of a releasable feed roll to run upon the under side of the platen, and means to displace said platen with the feed roll upwardly clear of said obstructing devices, to permit the introduction of a sheet downwardly in front and around the platen.
37. The combination with a revoluble platen and coöperative devices tending to obstruct the insertion of work-sheets at the front of the platen, of means to displace said platen upwardly to clear said obstructing devices, to permit the introduction of a work-sheet downwardly in front of the platen, and a paper-directrix normally behind said obstructing elements, and movable up relatively to the platen, to guide sheets, bottom foremost, downwardly around the platen.
38. The combination with a revoluble platen and coöperative devices tending to obstruct the insertion of work-sheets at the front of the platen, of a releasable feed roll to run upon the under side of the platen, means to displace said platen with the feed roll upwardly clear of said obstructing devices, to permit the introduction of a sheet
- downwardly in front and around the platen, and a collating board having gaging devices thereon for variably positioning the work-sheets which extend between the platen and said roll.
39. The combination with a revoluble platen, of a collating board arranged thereover, and having a row of sheet-engaging studs or devices thereon, to collate sheets which extend down around the platen, elements for coöperation with said platen, said elements tending to obstruct the introduction of sheets downwardly around the platen, and means for shifting said platen up away from said elements, to facilitate the introduction of sheets collated upon said board.
40. The combination with a revoluble platen, of a collating board arranged thereover, and having a row of sheet-engaging studs or devices thereon, to collate sheets which extend down around the platen, elements for coöperation with said platen, said elements tending to obstruct the introduction of sheets downwardly around the platen, means for shifting said platen up away from said elements, to facilitate the introduction of sheets collated upon said board, and a sheet-directrix normally lying behind said obstructing elements and movable up in front of the platen to guide sheets, bottom foremost, downwardly around the platen.
41. The combination with a revoluble platen, of a collating board arranged thereover, and having a row of sheet-engaging studs or devices thereon, to collate sheets which extend down around the platen, elements for coöperation with said platen, said elements tending to obstruct the introduction of sheets downwardly around the platen, means for shifting said platen up away from said elements, to facilitate the introduction of sheets collated upon said board, and a releasable feed roll running upon the under side of the platen and movable up therewith.
42. The combination with a revoluble platen, of a collating board arranged thereover, and having a row of sheet-engaging studs or devices thereon, to collate sheets which extend down around the platen, elements for coöperation with said platen, said elements tending to obstruct the introduction of sheets downwardly around the platen, means for shifting said platen up away from said elements, to facilitate the introduction of sheets collated upon said board, and a sheet-directrix normally lying behind said obstructing elements and movable up in front of the platen to guide sheets, bottom foremost, downwardly around the platen, the upper edge of said directrix forming a scale to coincide with the printing line on the platen when both the platen and the directrix are in their elevated positions.
43. The combination with a revoluble platen, of a collating board arranged there-

- over, and having a row of sheet-engaging studs or devices thereon, to collate sheets which extend down around the platen, elements for coöperation with said platen, said 5 elements tending to obstruct the introduction of sheets downwardly around the platen, means for shifting said platen up away from said elements, to facilitate the introduction of sheets collated upon said board, a sheet 10 directrix normally lying behind said obstructing elements and movable up in front of the platen to guide sheets, bottom foremost, downwardly around the platen, and means to coöperate with the platen to feed 15 sheets around the same when said directrix is in its retired position.
44. In a typewriting machine, the combination with a revoluble platen and devices to coöperate therewith, said coöperating 20 devices tending to obstruct the introduction of work-sheets at the front of the platen, of a main frame, a separate platen frame mounted upon the main frame, the platen being mounted in said separate 25 frame for upward displacement to clear said obstructing devices, means for maintaining said separate frame in an elevated position with the platen just clearing said obstructing devices for the downward insertion of 30 a work-sheet, and a line-spacing wheel mounted upon the main frame and having an operative connection with the platen, said connection movable to accommodate the upward displacement of the platen.
- 35 45. In a typewriting machine, the combination with a revoluble platen and devices to coöperate therewith, said coöperating devices tending to obstruct the downward introduction of work-sheets at the front of 40 the platen, of a frame in which said platen is mounted for up and down displacement, a main frame to which the first frame is hinged at a point in rear of the platen axis, means for maintaining said first frame in 45 an elevated position with the platen just clearing said obstructing devices for the downward insertion of a work-sheet, a line-space wheel upon said main frame, and gearing constantly connecting said line-space wheel to said platen to accommodate the up and down displacement of the latter.
- 50 46. In a typewriting machine, the combination of a revoluble platen, a frame in which said platen is journaled, and a case-shift frame upon which said platen frame is mounted, the first of said frames movable to give to said platen an independent upward displacement, away from printing position, and the second of said frames 55 mounted to give the platen an upward and downward case-shift movement.
47. In a typewriting machine, the combination of a revoluble platen, a frame in which said platen is journaled, a case-shift 60 frame upon which said platen frame is

mounted for independent upward and downward displacement of the platen, as well as for upward and downward case-shift movement, a line-space wheel mounted upon said case-shift frame, and a train of gearing 70 connecting said line-space wheel to said platen to accommodate the independent upward and downward displacement of the latter.

48. In a typewriting machine, the combination of a revoluble platen, devices to coöperate with said platen, said coöperating devices tending to obstruct the introduction of sheets downwardly at the front of the platen, a frame in which said platen is journaled, a case-shift frame upon which said platen frame is mounted for independent upward and downward displacement of the platen, as well as for upward and downward case-shift movement, a line-space wheel 85 mounted upon said case-shift frame, and a train of gearing connecting said line-space wheel to said platen to accommodate the independent upward and downward displacement of the latter.

49. The combination with a collating table having normally retired studs, of a revoluble platen, devices to coöperate therewith, said devices tending to obstruct the introduction of work-sheets at the front of 95 the platen, means to elevate said platen to clear said obstructing devices, and means for concomitantly projecting said studs.

50. The combination of a revoluble platen, a collating table at the delivery side 100 thereof, a vertical row of normally retired studs on said table, a feed roll to run upon the platen, and means for releasing said feed roll and concomitantly projecting said studs.

51. The combination of a revoluble platen and devices to coöperate therewith, said devices tending to obstruct the introduction of sheets downwardly at the front of the platen, a collating board at the delivery side of the platen in position to permit work-sheets to lie upon said board and at the same time extend around the platen, sheet-engaging studs upon said board and normally retired, and means for concomitantly elevating said platen clear of said obstructing devices and projecting said studs.

52. The combination of a revoluble platen and devices to coöperate therewith, 120 said devices tending to obstruct the introduction of sheets downwardly at the front of the platen, a collating board at the delivery side of the platen in position to permit work-sheets to lie upon said board and at the same time extend around the platen, 125 sheet-engaging studs upon said board and normally retired, means for concomitantly elevating said platen clear of said obstructing devices and projecting said studs, and a 130

releasable feed roll for said platen, said feed roll connected to be restored concomitantly with the retirement of said studs.

53. The combination of a revoluble platen, a frame wherein it is mounted for upward displacement, a case-shift frame to which said platen frame is hinged, a revoluble finger-piece mounted upon said case-shift frame, a train of gearing connecting said finger-piece to said platen to accommodate the upward displacement of the latter, a line-space wheel and detent for said platen, and a carriage upon which said case-shift frame is mounted.

54. The combination of a revoluble platen,

a frame wherein it is mounted for upward displacement, a case-shift frame to which said platen frame is hinged, a revoluble finger-piece mounted upon said case-shift frame, a train of gearing connecting said finger-piece to said platen to accommodate the upward displacement of the latter, a line-space wheel and detent for said platen, and a carriage upon which said case-shift frame is mounted.
